his Attorney.

UNITED STATES PATENT OFFICE.

JOHN A. LENNARTSON, OF ST. PAUL, MINNESOTA.

CRATE.

Application filed April 5, 1922. Serial No. 549,811.

To all whom it may concern:

Be it known that I, JOHN A. LENNARTSON, a citizen of the United States, residing at St. Paul, in the county of Ramsey and State 5 of Minnesota, have invented a new and useful Improvement in Crates, of which the following is a specification.

My invention relates to collapsible crates and has for its object to provide a crate 10 which may be readily collapsed into a flat condition or which may be quickly and rigidly erected for use.

Another object is to provide the crate with a lower base member to which the sides 15 of the crate are permanently pivoted and to provide a detachable cover adapted to be secured to the upper portions of the sides of the same.

A still further object is to provide attaching means for said cover on the base proper so that the cover may be attached to the base in like manner after the sides have been swung within the same so as to completely conceal and encase the same within the base.

Another object is to provide latching means at the corners of the sides by means of which the same are held in rigid relation to one another.

A still further object is to provide latching means on the ends and base of the crate adapted to engage the cover thereof so that the same may be latched in either erected or collapsed position.

A still further object is to form said last named latching means of a single wire member adapted to be slidably positioned within a groove formed in the rails included in the base and ends of the crate.

The full objects and advantages of my invention will appear in connection with the detailed description thereof and are particularly pointed out in the claims.

In the drawings, illustrating the application of my invention in one form:—

Fig. 1 is a perspective of my invention.

Fig. 2 is a longitudinal sectional view taken through the crate when the same is collapsed and drawn to a larger scale.

Fig. 3 is a detail sectional view of the hinge members used for attaching the sides of the crate to the base and drawn to an enlarged scale.

Fig. 4 is a sectional view taken on line 4—4 of Figure 3.

Fig. 5 is a plan sectional view of a corner

of the crate showing the means for latching the same together.

Fig. 6 is a plan sectional view of a portion of the upper rail of the ends of the crate drawn to a larger scale, showing the manner 60 of latching the same to the top of the crate.

My invention as best shown in Figure 1 comprises a base indicated in its entirety at A, which consists of side rails 10 to which are secured end rails 11 of a width somewhat 65 less than the said side rails. These two rails lie flush on the bottom and are connected by a number of slats 13 which are nailed to the end rails 11. This structure forms a container for holding the sides of the crate 70 to which the top or cover of the same may be attached.

The sides of the crate are indicated at B and C in Figure 2, and each consists of upper rails 14 and lower rails 15, which are 75 connected by means of a plurality of vertical slats 17 rigidly nailed thereto. The rails 15 are so positioned that the same rest upon the rails 10 of base A, so that the slats 17 lie flush with the interior of the said rails 10 80 when the crate is in erected position.

The ends of the rail are indicated at D and E and are similar in construction to the sides B and C. These ends consist of upper rails 18 and lower rails 19 which are connected by a plurality of vertical slats 20 in similar relation to the sides B and C. In like manner the rails 19 rest upon the end rails 11 of base A and may be supported 85 thereon.

For hinging the sides to the base A, I provide the following construction. As before stated the slats 17 of the side walls B and C extend inwardly along the interior surfaces of the rails 10, the said rails on the side C extending substantially down to the top of the slats 13 while in side B shortly below the center of the same. The corners 90 22 of said rails are beveled on the interior of the same as shown in detail in Figure 4. 100 A number of angle bars 21 are secured to the said slats and have one leg positioned along the side of the slat and the other along the end of the same. This forms a space along the beveled corners 22 through 95 which a rod 23 may be positioned. The rods 23 pass directly through the rails 11 and have a washer 24 positioned on the end of the same. By riveting over the extreme ends of these rods the said rods are securely 105 110

held in place, tying the ends of the box together and at the same time forming a substantial hinge on which the sides B and C may swing. The arrangement of the two rods 23 for the sides B and C is shown in Figure 1 with one rod positioned near the bottom and the other upwardly from the bottom of the base A. With this construction the sides B and C may be swung inwardly towards one another with the said sides adapted to lie one on top of the other with side C on the bottom and B on top. In a similar manner by means of rods 25 the ends D and E are pivoted to the side rails 10. For stiffening the structure and for supporting the ends D and E, I provide two cleats 26 and 27 which are attached to the interior of the rails 11 at the bottom of the box and which lie flush beneath the ends of the slats 18 when the said ends D and E are erected. Rods 25 pass through the base A shortly above the said cleats 26 and 27 as best shown in Figure 2.

For holding the corners of the box together I provide a device shown in detail in Figure 5. The same consists primarily of a U-shaped member 28 which is fastened by means of one leg 29 to the end slats 20 of the ends D and E of the crate. These U-shaped members are formed with inwardly turned tongues 30 which are adapted to engage in notches 31 formed in the outer surface of the slats 17. With this construction it can readily be seen that neither of the sides B and C or the ends D and E may be moved outwardly from one another in either direction, when the said members 28 are in proper position with the tongues 30 within the notches 31. For preventing inward movement of the said crate sides I provide a sliding bolt 32 attached to slats 17 which is adapted to engage within recesses 33 formed on the interior of slats 20. When these bolts are closed as shown in Figure 5 the corners of the crate are rigidly locked so that the same cannot move in any direction whatsoever.

In collapsing the crate bolts 32 are withdrawn and the parts may be swung inwardly with side C resting on the bottom, side B resting on top of side C and ends D and E positioned one on the other as clearly shown in Figure 2. The movement of the same is made possible by forming the ends D and E including the length of rails 18 and 19 of a width equal to the width between the rails 10 of base A. In a similar manner the sides B and C including the rails 14 and 15 are made of a width equal to the width between the slats 20 of ends D and E when the device is erected. This permits of the said sides being slid inwardly from disengagement with the tongues 30 of members 28 and into collapsed position and subsequently

of ends D and E and to the required positions.

The top of the crate indicated at F consists of two rails 34 of a thickness equal to the thickness of the rails 11 and 18 of a width equal to the difference in width between two rails 10 and of a length equal to the length of rail 18. These slats or rails are connected by a number of horizontally positioned slats 35 which are nailed thereto, the said slats being of such a length that the said rails 34 may rest upon the rails 18 and have their surfaces lie flush with the surfaces thereof.

For latching top F to the crate I provide a structure best shown in Figures 1 and 6. To the underside of the rails 34 at the center thereof are positioned two angular members 37 placed back to back as clearly shown in Figure 1. The depending portion of these members adapted to pass through notches 38 cut in the upper portions of the rails 18, which notches extend completely through said rails and downwardly within the same. Horizontally positioned along the outer face of each of the rails 18 is a slot 39 which may be cut within the same by means of a circular saw. This slot lies in a plane with a hole 40 drilled through the two depending portions of the angle members 37. A bolt 41 formed of a wire having a downwardly bent U-shaped portion 42 formed with an upwardly turned leg 43 is slidable within the groove 49 and is adapted to pass through the hole 40 in the angle members 37 so as to latch the said top F to the ends D and E when the said bolts are passed through holes 40 in the angle members. These bolts are held in place within notches 39 by means of two staples 44 which are pounded into the rails 18 as clearly shown in Figure 6. A spring actuated friction button 45 of ordinary construction is positioned in the rails 18 immediately back of the extreme portion of bolt 41 when the same is in its latched position. This serves the purpose of preventing the bolt from becoming accidentally unlatched when the same is not desired.

Upon manipulating bolt 41 by means of the leg 42 the same may be forced over button 45 into unlatched position. Due to the fact that the bolt 41 is formed with both downwardly and upwardly extending T heads as shown in Figure 1 the said bolt cannot rotate and the extreme end 43 of the same is prevented from accidental projecting outwardly where the same might easily catch on the garments of the passersby and tear the same.

In collapsing the crate the top F is completely removed and the sides and ends unlatched as previously described and swung inwardly. After this has been accomplished the top F is again replaced and positioned

upon the rails 11 where when a latching device indicated in its entirety at G is formed on the said rails 11 identical with that previously described. By means of this structure the top F may again be directly latched to the base A so that a compact structure is provided in which all of the members of the crate are contained.

The advantages of my invention are manifest. The device can be made extremely rigid and substantial and to undergo numerous shipments without being broken or otherwise rendered useless. In this manner considerable money can be saved. The 15 crate when erected is rigidly tied together at all its corners by latching means and the base proper is firmly held together by the tie rods forming hinges for the sides. The latching means for the top are of such nature as to prevent accidental removal of the same and at the same time firmly hold the top in place.

In accordance with the patent statutes I have described the principles of operation 25 of my invention, together with the apparatus which I now consider to represent the best embodiment thereof, but I desire to have it understood that the construction shown is only illustrative and that the invention can be carried out by other means 30 and applied to uses other than those above set forth within the scope of the following claims:

I claim:

- 35 1. A crate comprising a base, side and end walls pivotally connected to said base, and adapted to swing inwardly within the same, a cover, latching means formed on said base, and end walls, and means on said cover adapted to cooperate with either of said latching means to hold said cover in latched position in either erected or collapsed position of the crate.
- 40 2. A collapsible crate comprising a base formed of a plurality of rails, tie rods extending through said rails for stiffening and holding the same rigidly together, and end and side walls pivoted on said tie rods.
- 45 3. A collapsible crate comprising a base formed with side and end rails secured together, said end rails being of a width substantially less than the said side rails and being attached thereto with the bottom of the same lying flush, side walls pivoted to

said base, end walls pivoted to said base, rails formed on said side and end walls, said end wall rails being positioned below the side wall rails an amount equal to the difference in the width of said base rails, and a top having a pair of rails adapted to fit 55 on top of said end wall rails and said end base rails to lie flush with the top of said side walls or said base side rails as required, and means for latching said top rails to either of said end wall rails or base end 60 rails as desired.

4. A collapsible crate comprising a base having side and end rails, side and end walls positioned along said base, said side and end walls having a cut away corner 70 at the lowermost portion thereof, angular members secured to said side and end walls, extending across said cut away corners and rods extending through said base rails and passing between the apexes of said angles and the cut away corners of said end portions for hingedly connecting said side and end walls to the base.

5. A collapsible crate comprising a base, side and end walls hinged thereto, and U-shaped members secured to some of said walls and adapted to hook into adjacent walls for preventing the movement of any of said walls outwardly.

6. A collapsible crate comprising a base, side and end walls hinged thereto, and U-shaped members secured to some of said walls and adapted to hook into adjacent walls for preventing the movement of any of said walls outwardly, and a bolt for holding said walls from inward movement.

7. A collapsible crate comprising a base formed with end rails, walls pivotally connected to said base and adapted to swing inwardly towards one another into collapsed position, two of said walls having upper rail members, grooves formed in said base and wall rail members, slots formed in said rail members extending downwardly through said grooves, bolts slidable in said grooves, a top for said crate adapted to be positioned upon either of said rails, and means cooperating with said bolts secured to said top adapted to be extended down through either of said notches in proximity to said bolts.

In testimony whereof I affix my signature.
JOHN A. LENNARTSON.
